Patented September 20, 1904.

UNITED STATES PATENT OFFICE.

ERNEST MEYERS, OF TAUNTON, MASSACHUSETTS, ASSIGNOR TO REED AND BARTON CORPORATION, OF TAUNTON, MASSACHUSETTS.

DESIGN FOR A FORK, SPOON, OR SIMILAR ARTICLE.

SPECIFICATION forming part of Design No. 37,147, dated September 20, 1904.

Application filed July 28, 1904. Serial No. 218,553. Term of patent 14 years.

To all whom it may concern:

Be it known that I, ERNEST MEYERS, of Taunton, in the county of Bristol and State of Massachusetts, have invented a new, original, and ornamental Design for Forks, Spoons, or Similar Articles, of which the following, taken in connection with the accompanying drawings, is a specification.

Figure 1 is a front plan view of a fork or spoon, showing my design; and Fig. 2 is a

plan view of the opposite or rear side of the fork or spoon.

I claim as my invention—

The ornamental design for a fork, spoon or similar article, as shown.

ERNEST MEYERS.
